UNITED STATES PATENT OFFICE.

JAMES L. RAY, OF ESSINGTON, PENNSYLVANIA, ASSIGNOR TO WESTINGHOUSE ELECTRIC & MANUFACTURING COMPANY, A CORPORATION OF PENNSYLVANIA.

TURBINE-NOZZLE MANIFOLD.

Application filed March 28, 1924. Serial No. 702,492.

My invention relates to steam turbines having a rotor with a plurality of blades carried thereby and a group of nozzles for expanding the steam and directing it against the blades, and has for an object to provide an improved nozzle manifold therefor which shall be simple of design, easy to manufacture and capable of resisting relatively high pressures of steam.

10 Another object of my invention is to provide apparatus of the character designated forged from one piece of metal which shall be of curved outline to accommodate itself to the periphery of the rotor and shall have 15 a smooth curved passage therein for the distribution of steam.

A further object of my invention is to provide a method of making apparatus of the character designated from one piece of 20 forged steel.

These and other objects are accomplished by my improved apparatus and the method of making the same illustrated in the accompanying drawings of which Fig. 1 is 25 a cross section of a turbine with a portion of the rotor cut away, the nozzles removed and having my improved nozzle manifold applied thereto; Fig. 2 is a sectional view of the nozzle manifold taken along the line 30 II-II of Fig. 1 and also showing in section a nozzle box attached to the manifold and a portion of the rotor disc with its blades; Fig. 3 is a view of a forging illustrating the first steps in the making of my improved 35 manifold; Fig. 4 is an end view of Fig. 3; and Fig. 5 is a view illustrating a further step in the making of the manifold.

Heretofore, in the design of steam turbines operating at pressures up to 350 40 pounds per square inch, nozzle manifolds, as known to me, have been cast and provided with an opening along one side to which the nozzles are attached. To enable such manifolds to withstand the pressures 45 to which they are subjected, it has been necessary to rigidly stay them with stay bolts.

In the more recent development of steam turbines, higher pressures are employed 50 than was formerly the case, so that at the present time, pressures up to 1200 pounds per square inch are not unheard of. As the pressures employed have increased it has become more and more difficult to provide 55 a nozzle manifold of sufficient strength and

rigidity to withstand the pressure to which it is subjected and, due to the great amount of staying required, to provide for a free passage and distribution of steam to the nozzles.

To solve these difficulties, it has been proposed to cast a manifold with integral ribs or stays, but such a construction has, like its predecessors, been difficult to make so as to have the necessary strength and to provide, at the same time, for a proper distribution of steam to the nozzles.

To overcome the aforementioned difficulties, I provide a nozzle manifold made from one piece of forged metal, preferably steel. 70 In the construction of this manifold a bar or block of the metal of the desired size is first taken and is provided with a main distributing passage for the steam. The block is afterward heated, bent to the required shape, cooled and finished by machining.

For the distribution of steam to the nozzles, I provide in the face of the manifold, a distributing channel and connect this 80 channel to the main steam passage of the manifold by ports sufficiently spaced as to leave ample metal between them to maintain a structure of great strength and rigidity.

Referring now to the drawings for a better understanding of my invention, I show in Fig. 1 a steam turbine having a rotor 10 carrying blades 11. For expanding the steam and directing it against the blades, 90 I show in Fig. 2 nozzles 12 and 13. The nozzles 12 and 13 are secured to my improved nozzle manifold 14 by any suitable means such as wedges 16 and studs 17, the latter screwed into the face of the manifold 14.

The manifold 14 is made from one piece of forged metal and is supported in the turbine by any suitable means, such as by studs 15. It is curved in an arcuate shape 100 to permit attachment of the nozzles 12 and 13 in an arc conforming with the periphery of the turbine rotor 10. A main distributing passage 18 extends from end to end of the manifold and is curved in the same 105 general direction. A supply conduit 19 conveys steam to the manifold and a passage 21 leads from the supply conduit 19 to the distributing passage 18. The distributing passage 18 is closed at each end as by plugs 110

22 and 23 which may, after insertion, be welded in place.

For conveying the steam from the distributing passage 18 to the nozzles, a suitable 5 number of holes or ports 24—24 lead therefrom to a distributing channel 26 machined in the face of the manifold 14. The holes or ports 24—24 are so spaced as to maintain a strong and rigid structure along the 10 side of the main passage 18 capable of withstanding the high steam pressure therein.

The nozzles 12 as before pointed out are secured to the face of the manifold 14 and are in communication with the distributing 15 passage 18, through the holes or ports 24—24 and the distributing channel 26.

In making the manifold 14, I first forge 20 a block or bar of metal, preferably steel, to a rectangular shape as shown in Figs. 3 and 4 and having a rectangular projection 27 intermediate the ends thereof. While in the rough, I drill the distributing passage 18 from end to end of the bar, after which the bar is heated and bent to the desired shape 25 as shown in Fig. 5. In order to prevent distortion of the passage 18 in the process of bending, I fill it with sand or other refractory material before bending. The passage 21 is next formed in the manifold, being 30 drilled through the rectangular projection 27 into the passage 18. After this step the face of the block is machined to form the distributing channel 26 and arranged for the 35 attachment of the nozzles 12 and 13. In this operation, the holes or ports 24—24 are formed leading from the distributing channel 26 to the passage 18. The manifold is then finally finished and means provided for securing the same in the turbine.

40 From the foregoing, it will be apparent that I have invented a nozzle manifold simple of design and capable of withstanding very high pressures and that I have provided a simple method of making the same 45 from one piece of forged metal.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

55 What I claim is:—

1. A high-pressure turbine nozzle manifold formed from one piece of forged steel, and having therein a circumscribed curved distributing passage and a plurality of ports

communicating therewith, said ports being 60 so spaced as to leave sufficient metal around said passage to withstand the high pressure therein.

2. In a high-pressure elastic fluid turbine having a rotor with a plurality of blades 65 carried thereby, a nozzle manifold made of one piece of forged steel and bent to an arc conforming to the periphery of the turbine rotor, said manifold having a passage extending therethrough in a concentric arc, 70 means providing a plurality of expansion nozzles disposed along said passage for directing elastic fluid against said blades, said manifold having a plurality of ports leading from said passage to said nozzles, said 75 ports being so spaced as to provide sufficient metal therebetween to withstand the high pressure in said passage, and a steam supply passage leading to said passage.

3. In a high-pressure elastic fluid turbine 80 having a rotor with a plurality of blades carried thereby, a nozzle manifold made of one piece of forged steel and bent to an arc conforming to the periphery of the turbine rotor, said manifold having a passage extending therethrough in a concentric arc, 85 means providing a plurality of expansion nozzles disposed along said passage for directing elastic fluid against said blades, said manifold having a plurality of ports leading 90 from said passage to said nozzles, said ports being so spaced as to provide sufficient metal therebetween to withstand the high pressure in said passage, means closing the ends of 95 said passage, and a steam supply passage leading to said curved passage.

4. In a steam turbine having a rotor with a plurality of blades carried thereby and a group of nozzles for expanding the steam and directing it against the blades, a one-piece forged nozzle manifold curved to permit attachment of the nozzles in an arc conforming with the periphery of the turbine rotor, said nozzle manifold having a steam supply passage communicating with a supply 100 conduit, a smooth curved passage extending therethrough for the distribution of steam to the nozzles, said passage being closed at each end, a distributing channel in the face of the manifold communicating with the nozzles, and a plurality of ports connecting the distributing channel with the curved 105 passages.

In testimony whereof, I have hereunto 110 subscribed my name this 17th day of March, 1924.

JAMES L. RAY.
